(57) **CLAIM**

I claim, the ornamental design for a low profile light bar for emergency vehicles, as shown and described.

DESCRIPTION

FIG. 1 is a top, view for a low profile light bar for emergency vehicles showing my new design;

FIG. 2 is a left view thereof;

FIG. 3 is a bottom view thereof;

FIG. 4 is a front view thereof;

FIG. 5 is a right view thereof;

FIG. 6 is a back view thereof;

FIG. 7 is an isometric view thereof; and,

FIG. 8 is a view of the low profile light bar for emergency vehicles mounted on the roof of vehicle.

The broken lines in FIG. 1, FIG. 3 and FIG. 7 depict environmental subject matter of mounting hardware for the invention and form no part of the claimed design.

The broken lines in FIG. 8 depict environmental subject matter of mounting hardware for the invention on a vehicle only and form no part of the claimed design.
